ABSTRACT OF THE DISCLOSURE

A contact fuzing system for providing a plurality of triggering elements without one triggering element interfering with another. A plurality of triggering elements positioned over an area of expected impact with a target are coupled by means of an isolating circuit to the processing circuit which generates the firing pulse.

The invention herein described may be manufactured and used by or for the Government of the United States of America for governmental purposes without the payment of any royalties thereon or therefor.

The present invention relates to contact fuzing systems and more particularly to contact fuzing systems having multiple triggering elements.

For greater reliability of the ignition of a contact type fuze, it has been found necessary to install multiple triggering devices positioned over an area of that portion of the missile expected to collide with the target. It is also desirous that the contact fuze will initiate the missile warhead on the first shock pulse reaching anyone of the various triggering devices. The present invention provides a contact fuze system which will accomplish the above requirements by initiating the warhead whether the shock pulse is negative or positive and provides isolation of the signals generated by the triggering devices to prevent distortion of the initial triggering signal.

Accordingly, an object of the present invention is to provide an improved contact fuze system which utilizes multiple triggering devices without interference of one triggering output signal with any of the other triggering output signals.

Other objects and many of the attendant advantages of this invention will become readily appreciated as the same becomes better understood by reference to the following detailed description when considered in connection with the accompanying drawings wherein:

FIG. 1 is illustrative of a missile with a plurality of fuze triggering devices positioned on its outer surface.

FIG. 2 is a block diagram of a preferred embodiment of the invention.

FIG. 3 is a schematic diagram of the embodiment of FIG. 2.

Referring now to the drawings there is shown in FIG. 1 a missile 10 having a plurality of triggering devices 12 strategically located on its forward portion. Devices 12 are positioned on each of the wing hubs 14 and near the nose of the missile on a structural member 16 near the skin surface of the missile 10. These positions are selected so that if any portion of a wing or a portion near the nose is impacted, the shock wave will be transmitted to the triggering devices 12.

Referring to FIG. 2, any shock wave detected by any of triggering devices 12 produces output signals which are fed to fullwave rectifier and mixer 18. The output signal from fullwave rectifier and mixer 18 is picked off by the movable tap 20 of a potentiometer 22.

The signal appearing at movable tap 20 is fed to buffer amplifier and limiter 24 which isolates the remainder of the circuit from triggering devices 12. This is necessary so that the inductance and capacitance of the filter circuit of low pass filters and DC coupler 26 will not react with electromechanical properties of the triggering devices 12 and cause resonant humps in the frequency response. The output from low pass filters and DC coupler is fed to peak detector and blocking oscillator 28 which provides an output signal to output circuit 30 when the blocking oscillator is triggered by a detected signal of a predetermined amplitude. In order to minimize the probability of an early firing, supply voltage to output circuit 30 is supplied by enabling switch 32 just prior to anticipated intercept of the target.

Referring to the schematic diagram of FIG. 3, any signals generated by triggering devices 12 (FIG. 1) are fed through input resistors 13 to the primary windings of full wave rectifier transformers 15. The centertapped secondaries of transformers 15 are connected to diodes 17 for full wave rectification. The outputs from rectifiers 17 are connected to the fixed terminal potentiometer 19. The full wave rectified signals do not add because the maximum signal at any instant back biases the other rectifier diodes, therefore, the instantaneous mixer output amplitude is proportional to the triggering device output which is instantaneously maximum.

The gain of the output signal from full wave rectifier 18 may be attenuated by means of adjusting movable tap 20 of potentiometer 19. The signal picked off by movable tap 20 is coupled to the base of transistor 25 which acts as an isolator to isolate filter 26 from the triggering devices 12 and to limit the output signal to approximately 1.4 times the amplitude of a signal which would produce a fuze firing signal. Resistor 51 and Zener diode 53 act as a voltage regulator to keep the voltage across resistors 55 and 57 constant. The voltage applied to the collector of transistor 25, when it is non-conducting, is the result of the Zener regulated voltage and the divider ratio of resistors 55 and 57. The open circuit (nonconducting) voltage of transistor 25 and its source impedance determine the voltage level at which amplifier 24 will limit.

Low pass filter 26 should have filter roll-off characteristics such that the amplitude of its output to peak detector 28 at 12,500 c.p.s. is approximately 0.7 of that which would occur at 8,000 c.p.s. with the same gain adjustment and input signal amplitude. The expression, limiter output X filter gain = input to peak detector, defines the filter = limiter action.

The output of low pass filter 26 is coupled through capacitor 27 to the input of peak detector and blocking oscillator 28. The peak detector consists of a reverse-biased transistor 29 which provides a blocking oscillator pulse when the input at its base exceeds the reverse bias. Resistor 31 should be of a sufficient value to hold the blocking oscillator in a quiescence state. When a positive DC signal exceeding the preset bias value is applied to the base of transistor 29, the blocking oscillator will free run at a predetermined frequency.

Output circuit 30 releases electrical energy stored in capacitor 33 to output terminal 35. The above is accomplished as follows: as the blocking oscillator pulses a signal is coupled into winding 37 of transformer 39 to drive the gate of silicon controlled rectifier 40 positive with respect to the cathode, thus, allowing capacitor 33 to discharge.

Under missile flight conditions, +26.5 v. DC is applied to terminal 41 energizing all of the circuit up to but not including, the output circuit 330. Capacitor 33 will not be charged until it is connected to an energizing voltage at terminal 42 when a signal is applied (from the missile) to

terminal 43 to energize relay coil 44 which closes relay 45.

What is claimed is:

1. In a contact fuze system for a missile carrying a warhead to be exploded on contact with a target, the combination comprising:

- (a) a plurality piezoelectric means positioned at various positions of expected impact between the missile and target and being responsive to acceleration forces as a result of an impact between the target and missile to generate voltages proportional to acceleration, 10
- (b) a plurality of transformers, each having a primary winding and a centertapped secondary winding,
- (c) one end of each of said primary windings and the centertaps of said secondary windings being connected to a common ground,
- (d) the other end of each of said transformer windings being connected respectively to one of said piezoelectric means,
- (e) dual diode fullwave rectifier means connected across each of said secondary windings,
- (f) a potentiometer having a movable tap and being connected between the outputs of said fullwave rectifier and the common ground, whereby the maximum voltage generated by any one of said piezoelectric

5

means will appear at the movable tap of said potentiometer,

(g) signal processing circuit means coupled to said movable tap for generating a fuze firing pulse in response to the voltage output of said coupling means,

2. The contact fuze system of claim 1 wherein said signal processing circuit comprises:

- (a) a buffer amplifier and limiter coupled to the output of said isolation coupling means,
- (b) low pass filter circuit means having a filter gain less than 0.70 for all frequencies greater than 12.5 kc. coupled to the output of said buffer amplifier,
- (c) peak detector circuit means including a blocking oscillator coupled to said low pass filter circuit means for generating an output signal when the output of said buffer amplifier reaches a predetermined value.
